CLAIM

The ornamental design for an ice cream package, as shown and described.

DESCRIPTION

FIG. 1 is a plan view of an ice cream package;

FIG. 2 is a front elevational view of an ice cream package of the invention

FIG. 3 is a left side elevational view of an ice cream package of the invention;

FIG. 4 is a right side elevational view of an ice cream package of the invention;

FIG. 5 is a rear elevational view of an ice cream package of the invention; and,

FIG. 6 is a bottom plan view of an ice cream package of the invention.

Broken lines depict portions of the environment that form no part of the claimed design.

1 Claim, 4 Drawing Sheets
